ROTARY WELL DRILLING APPARATUS

Guy K. Claire, Rolling Hills, Calif., assignor of
one-third to Arthur L. Armentrout, one-third to
Elwin B. Hall, and one-third to Virgil P. Baker,
all of Los Angeles, Calif.

Application March 10, 1939, Serial No. 260,971

18 Claims. (Cl. 255—23)

This invention relates to well drilling equipment and relates more particularly to a rotary table or rotary for use in the rotary method of well drilling. A general object of this invention is to provide a practical effective and improved rotary table for rotating the well strings and for performing the other functions of typical rotary tables and for making up and breaking down the drilling strings and other sectional well strings.

In the rotary method of well drilling a power driven rotary table is provided in the derrick to carry the bushings, slips and other devices for supporting and engaging the tool-carrying drilling strings, the casing strings, etc. A well string such as a rotary drilling string is made up of a plurality of stands of pipe connected by threaded couplings and during the drilling operation a polygonal or fluted kelly is connected in the upper portion of the string to operate through the rotary table. The kelly is engaged by a correspondingly shaped bushing in the rotary table to provide a rotary transmitting drive between the table and the drilling string. In making up and breaking down a rotary drilling string it is the general practice to support the string in the table by means of slips and to turn the uppermost stand of pipe while securing the lower portion of the string against rotation. One set of tongs is usually engaged about a section of the tool joint at the table and another set of tongs is engaged about the other section of the tool joint. The last named set of tongs is usually operated by a line handled by a cathead of the draw works. The operation of the tongs and the lines is a time consuming operation and is accompanied by considerable danger to the workmen and equipment. Furthermore, in making up the threaded connections by tongs and a jerk line it is difficult, if not impossible, to gauge the torsion applied to the connections and in many cases the threads of the pipe connections are galled or strained endangering the entire well string and shortening the life of the joints.

Rotary tables known as make and break rotaries have been proposed to facilitate the making up and breaking down of the well strings. These make and break rotary tables usually embody inner and outer independently rotatable table parts with means on the inner table part to hold the pipe against turning and means on the outer table part to turn the upper stand of pipe. In these so-called make and break rotary tables the drive for the main inner table part, used during drilling operations, is utilized to rotate the outer part in making up and breaking

down the well strings. This use of the main power means of the rotary table to drive the outer table part is very unsatisfactory in many respects. For example, it necessitates a special 5 complicate means for connecting and disengaging the inner and outer parts of the table and requires the continuous operation of the rotary engine throughout the making and breaking operations. Furthermore, the make and break rotary tables that have been proposed do not embody practical or effective means for gauging the torque applied to the threaded connections of the well strings. It has been proposed that friction brake means be utilized to hold one section of 10 the table against turning during the making up of the threaded joints, which brake means will release when a given torque is applied to the threaded connections. Such brake means are impractical, are not dependable, and do not assure the uniform application of torque to the many joints of the drilling string.

Another object of this invention is to provide a rotary or a rotary table operable to make up or thread together the joints of a rotary well drilling string under a given uniform torque or 15 rotational force to assure the dependable connection of the string sections and to prevent galling and straining of the threads.

Another object of this invention is to provide 20 a rotary table operable to make up and break down sectional well strings that embodies an automatic torque governed drive or power means for rotating one part of the table, which power means may be set or conditioned to make up the 25 joints under a given or selected uniform rotational force.

Another object of this invention is to provide 30 a rotary table of the character mentioned embodying a ring or outer part rotatable relative to the inner table part to make up and break down the threaded connections of the well strings and a separate drive and power means for 35 rotating the said outer part. The improved rotary table of the present invention embodies a drive of suitable or customary form for rotating the main inner table part and a separate drive and power means for operating the outer table part to break and make the threaded joints of the well strings.

Another object of this invention is to provide 40 a rotary table of the character mentioned in which the drive for the outer table part may be utilized as an emergency drive or special drive for rotating the entire table and this drive is 45 torque controlled thereby adapting the rotary ta-

ble for use in special drilling operations, etc. where a torque controlled rotation of the well string is necessary. The drive for the outer table part is very important as it assures the continued operation of the drilling string in the event the regular drive fails and, therefore, makes it unnecessary to provide an expensive auxiliary drive means for the table.

Another object of this invention is to provide a rotary table of the character mentioned embodying novel, dependable and safe means for supporting the pipe engaging tongs on the base and outer table part for easy manual movement between their operative positions about the pipe and retracted positions clear of the rotary table bushings. The tong supporting means of the present invention are such that the tongs may be retracted to positions where they do not interfere with the drilling operations at the rotary table and are such that the tongs may be handled with little or no danger to the workmen.

Another object of this invention is to provide a rotary table of the character mentioned in which the drive for the outer table part is fully controlled by simple, manual operations of a switch and brake located at a convenient station.

A further object of this invention is to provide a rotary table of the character referred to including novel practical and effective means for supporting the rotatable outer table part.

A still further object of this invention is to provide a rotary table of the character mentioned embodying means for visibly indicating the rotational force being applied while making up the joints or connections.

The various objects and features of my invention will be fully understood from the following detailed description of a typical preferred form and application of the invention, throughout which description reference is made to the accompanying drawings, in which:

Fig. 1 is a top or plan view of the rotary table of the present invention showing the tongs in the operative positions. Fig. 2 is an enlarged fragmentary vertical detailed sectional view taken substantially as indicated by line 2-2 on Fig. 1. Fig. 3 is an enlarged fragmentary vertical detailed sectional view taken as indicated by line 3-3 on Fig. 2. Fig. 4 is an enlarged fragmentary vertical detailed sectional view taken substantially as indicated by line 4-4 on Fig. 1. Fig. 5 is an enlarged fragmentary vertical detailed sectional view taken as indicated by line 5-5 on Fig. 1 with the motor, reduction gearing and other parts in side elevation. Fig. 6 is an enlarged vertical detailed sectional view taken substantially as indicated by line 6-6 on Fig. 5 with the motor in elevation. Fig. 7 is an enlarged fragmentary vertical detailed sectional view taken as indicated by line 7-7 on Fig. 5. Fig. 8 is an enlarged fragmentary vertical detailed sectional view taken as indicated by line 8-8 on Fig. 5 with the brake means in elevation. Fig. 9 is a fragmentary side elevation of the brake means taken as indicated by line 9-9 on Fig. 8. Fig. 10 is a wiring diagram of the circuits embodied in the torque controlled operating means of the outer table part. Fig. 11 is a side view of a bar for connecting the table parts. Fig. 12 is an enlarged fragmentary horizontal detailed sectional view taken as indicated by line 12-12 on Fig. 5, and Fig. 13 is an enlarged fragmentary vertical sectional view taken as indicated by line 13-13 on Fig. 1.

The improved rotary table of this invention

may be said to comprise, generally, a base 10 to be mounted at the upper end of the well, an inner table part 11 rotatably supported on the base 10, drive means 12 for rotating the inner table part 11, a ring or outer table part 13 rotatably supported on the base 10, torque controlled means 14 for driving or rotating the outer table part 13, tong supporting means 15, and other elements the functions and details of which will be subsequently described.

The base 10 is provided to support the various operating elements of the apparatus and is adapted to be suitably mounted on the floor of the well derrick. The base 10 is provided with a generally rectangular lower part 16 to be secured to the supports of the table. The base 10 further includes an upstanding annular inner wall 17 surrounding or defining the central vertical opening 18 of the base and an upstanding outer wall 19 spaced some distance from the wall 17. Webs 20 extend between and connect the lower portions of the spaced walls 17 and 19. An upstanding intermediate wall 21 is spaced between the inner and outer walls 17 and 19 and is somewhat higher than the inner wall 17. An annular flange 22 projects upwardly and outwardly from the outer wall 19 to support the outer part 13 of the rotary table, as will be later described. A lateral or radial tubular extension 23 is provided at one side of the base 10 to receive certain parts of the drive 12 for the inner table part 11. The extension 23 extends below the flange 22 and its opening 24 continues inwardly through the outer base wall 19.

The inner table part 11 is provided to carry the bushings, slips, etc. employed in the various well drilling operations. The inner part 11 of the rotary table is an annular member or structure arranged in the base 10. In the preferred construction the inner table part 11 includes a main upper portion 25 overlying the inner wall 17 of the base 10 and the channel or space between the walls 17 and 21. A tubular depending flange 26 on the upper portion 25 extends downwardly through the opening 18 in overlapping relation to the inner wall 17 of the base 10. A suitable anti-friction bearing 27 is seated in the base 10 between the walls 17 and 21 to rotatably support the inner part 11. The bearing 27 is seated against shoulders on the portion 25 and the wall 21 to take lateral thrusts as well as the vertical loads. An apron ring 28 is threaded to the lower portion of the flange 26 and has an annular upwardly facing channel 29. A bearing 30 is seated in the channel 29 to engage upwardly against a base web 20 for the transmission of upward and lateral thrusts from the inner table part 11 to the base 10. A suitable lubricant is provided in the channels of the base 10 carrying the bearings 27 and 30 and the adjacent portions of the base 10 and the inner part 11 mesh or overlap to seal off the bearing carrying channels.

The inner element or part 11 of the rotary table is annular, being provided with a central vertical opening 31 for receiving the bushing elements. The upper portion of the opening 31 is polygonal while the portion of the opening 31 extending through the flange 26 may be cylindrical. An upwardly facing shoulder 32 occurs on the wall of the opening 31 between its cylindrical and polygonal portions. A master bushing 33 is arranged in the opening 31 to seat on the shoulder 32. The upper portion of the bushing 33 is shaped to conform to the polygonal part of the opening 31 so that the bushing turns with

the table part 11. The opening 34 in the master bushing 33 has a polygonal upper part for receiving correspondingly shaped portions of kelly bushings, etc. The lower portion of the bushing opening 34 is tapered or conical to receive slips 35. As illustrated in the drawings the slips 35 may be seated in the opening 34 to grip and support a well string S.

The drive means 12 for rotating the inner table part 11 is provided to drive the table part 11 during the regular drilling operations, etc. The drive means 12 includes a ring gear 36 secured to the inner table part 11. The ring gear 36 may be integral with the main upper portion 25 of the table part 11 or may be a separately formed annular element rigidly engaged about the portion 25 as illustrated in the drawings. The upper surface of the ring gear 36 is preferably flush with the top surface of the portion 25 and the master bushing 33. The lower side of the ring gear 36 has an annular series of bevel gear teeth 37. An annular groove 38 in the under side of the gear 36 receives a reduced upper edge portion of the intermediate base wall 21 to provide a seal.

The drive means 12 for the inner table part 11 further includes a substantially horizontal shaft 39 extending inwardly through the opening 24 in the table extension 23. Suitable bearings 40 support the shaft 39 for free rotation. The shaft 39 may be driven by any suitable power means. In the case illustrated a sprocket 42 is keyed to the projecting outer portion of the shaft 39 and a chain 43 operated by the drilling engine (not shown) meshes with the sprocket 42 to rotate the shaft 39. A bevel pinion 44 is fixed or keyed to the inner end portion of the shaft 39 to mesh with the teeth 37 of the ring gear 36. Suitable means controlled by manual levers 45 are provided in the extension 23 to lock the shaft 39 and the inner table part 11 against rotation. The details of this shaft holding means are not shown as they are well known to those skilled in the art. The base 10 has a chamber 46 for carrying a bath of lubricant for the pinion 44 and the other operating parts. The upper portion of the outer base wall 19 is received in an annular groove 47 in the ring gear 36 to form a seal between the ring gear and the base. The inner table part 11 driven by the means 12 just described is, of course, controlled by the driller in the usual manner.

The outer table part 13 surrounds the inner part 11 and serves to carry one unit of the tong supporting means 15. In accordance with the invention the outer table part 13 is in the nature of a ring surrounding the ring gear 36 with some clearance. It is preferred to arrange the table part 13 so that its upper surface is in substantially the same plane as the top surfaces of the inner part 11 and the ring gear 36. The outer table part 13 overlies the base flange 22 and is supported on the flange 22 by anti-friction bearing means 48. The bearing means 48 may comprise a series of balls cooperating with annular races in the flange 22 and an annular section 49 fixed to the outer table part 13. The section 49 may be pressed into the part 13 or otherwise fixed to it. The base flange 22 is designed to carry a lubricant bath for the bearing means 48. The upper edge portion of the flange 22 is received in a groove 50 in the table part 13 to form a seal. Means is provided to prevent upward movement of the outer table part 13. A plurality of circumferentially spaced posts 51 is secured to the outer base wall 19. The posts 51

51 extend upwardly through openings in the flange 22 and carry rotatable rollers 52 cooperating with a track 53 in the section 49 of the table part 13. The rollers 52 engaging in the track 53 prevent tilting and upward movement of the outer table part 13. A ring 54 is provided to close the annular space between the ring gear 36 and the outer table part 13. The ring 54 may be secured to the posts 51 by screws 54a. In the preferred construction the ring 54 is designed to partially overlie the outer table part 13 to more effectively prevent the entrance of water, dirt, etc. to the flange 22.

The means 14 for driving or rotating the outer table part 13 is an important feature of the invention. The means 14 is operable to rotate the outer table part 13 relative to the inner table part 11 in both the righthand and the lefthand directions. In accordance with the invention the means 14 embodies an automatic torque control whereby the rotary table is operable to make up the numerous joints of a well string under a uniform rotational force of a selected intensity.

The drive means 14 includes a supporting bracket 55 projecting outwardly or radially from the outer wall 19 of the base 10 (see Fig. 5). The bracket 55 is suitably fixed to the base wall 19 and preferably projects outwardly in spaced diverging relation to the base extension 23. The power generating unit of the drive means 14 is mounted on the bracket 55. The power generating unit of the means 14 is preferably in the nature of a reversible electric motor 56 of a suitable rating, it being apparent that other equivalent prime movers may be employed as the power generating unit of the means 14. The motor 56 is preferably of an explosion-proof type. In the preferred construction the motor 56 is arranged so that its shaft 57 is radial relative to the common axis of rotation of the table parts 11 and 13. A suitable coupling 58 connects the inner end of the motor shaft 57 with the shaft 59a of a geared speed reduction unit 60. The speed reduction unit 60 is suitably fixed to the bracket 55 and the inner end of its shaft 59 projects inwardly under the table part 13. In accordance with the invention the motor 56 is supported to swing or turn on its axis under the influence of torque or driving load. A cradle 61 is fixed to the under side of the motor 56 and has inner and outer arms 62 and 63 projecting upwardly at the opposite ends of the motor. A bearing post 64 projects upwardly at the outer end of the bracket 55 and has a bearing 65 rotatably supporting the outer end of the motor shaft 57. The arm 62 of the cradle 61 has a bearing 66 adjacent the bearing 65 assisting in supporting the motor shaft 57. The inner cradle arm 63 has a similar bearing 67 receiving the shaft 59a of the speed reduction unit 60. It will be seen that the cradle 61 assists in supporting the motor 56 and is swingable or turnable with the motor. The cradle 61 forms a movable element of the automatic torque control, as will be subsequently described.

The drive means 14 further includes an annular series of bevel gear teeth 68 on the under side of the outer table part 13. A pinion 69 is keyed or fixed to the inner portion of the shaft 59 and meshes with the teeth 68. The flange 22 of the base 10 is formed to receive the pinion 69 and to contain a lubricant bath at the pinion. It will be seen that the motor 56 is operable to rotate the outer table part 13 through the medium of

the speed reduction unit 60 and the meshing teeth 68 and the pinion 69.

The automatic torque control for the motor 56 includes a yielding means resisting turning of the motor resulting from a torque load on the motor when the same is rotating the table part 13 in a righthand direction in making up the connections of the string S. The means for resisting swinging or turning of the motor 56 may include a web 71 on the cradle and a helical spring 75 arranged against the web 71. A pin 76 is provided on the web 71 to hold the spring 75 against displacement. The outer end of the spring 75 is arranged against a part to be later described and the spring serves to resist turning or swinging of the motor 56.

In referring to Fig. 10 of the drawings it will be seen that the energizing circuit of the motor 56 includes incoming power leads 78 extending from a suitable source of electrical energy. The leads 78 extend to a reversing switch 79 for controlling the reversible motor 56. The switch 79 may be of any suitable form of remotely controlled reversing switch. For example, it may be a magnetic reversing switch of any well known type. Leads 80 extend from the switch 79 to the motor 56 and the reversing switch 79 has a control circuit 81. A manual switch 82 is connected in the circuit 81 and is adapted to be operated to cause forward and reverse energization of the motor 56 and de-energization of the motor. The switch 82 may be a push button switch having a forward button 83, a stop button 84 and a reversing button 85. The manual switch 82 is preferably located for convenient operation by the operator or driller. In practice I prefer to mount the switch 82 on a post 86 projecting upwardly from the base portion 16 adjacent the base extension 23.

Visible indicating means is provided to indicate the rotational force or torque being applied in making up the couplings and in performing other operations. This means includes a pressure gauge 70, that may be mounted on the post 86. The gauge 70 is calibrated in thousands of foot-pounds. A pipe or conductor 72 leads from the gauge to a diaphragm 73 supported by a bracket 74 on the bracket 55. The diaphragm 73 may be of the Sylphon type or of the type shown. The outer end of the above described spring 75 engages a head 77 on the diaphragm 73. When the cradle 61 swings under the motor torque the spring 75 transmits force to the diaphragm 73 and the gauge 70 indicates the torque force being applied to the coupling or work. The diaphragm head 77 is shaped to retain the outer part of the spring 75. The operator observing the gauge 70 may operate the switch 82 to make up the couplings at any selected torque force or rotational force.

The automatic torque control of the drive 14 further includes a stop switch or limiting switch 87 connected in the common lead 88 of the control circuit 81 between the switch 82 and the reversing switch 79. The limiting switch 87 is mounted on the bracket 55 for adjustment toward and away from the web 71 and has a projecting pivoted or turnable operating part 89. The switch 87 is positioned so that its operating part 89 is engaged and moved by the web 71 of the cradle 61 when the motor 56 swings under the influence of a load of a given intensity. As illustrated in the drawings, the switch 87 has a pin 130 shiftable in a slot 131 in the bracket 55. A screw 132 is threaded 75

through an opening in a lug 133 on the bracket 55 and cooperates with the switch 87 to adjust the same relative to the cradle web 71. The screw 132 may be manipulated to adjust the switch 87 to be operated by the web 71 when any selected torque or force is applied to the work.

A finger 135 on the switch 87 cooperates with a scale 136 on the bracket 55 to indicate the position of the switch in terms of the foot-pounds of torque on the work required to cause operation of the switch. The switch 87 may be spring urged to the closed position and actuation of the part 89 by the web 71 effects opening of the switch 87. The stop button 84 of the switch 82 and the limiting switch 87 are both operable to open the circuits to the coils or magnetic means of the reversing switch 79 to effect de-energization of the motor 56. A lock nut 137 may be employed to lock the adjusting screw 132 in any selected position.

It may be desired to control the drive means 14 by the torque load to effect de-energization of the motor 56 when the table part 13 is being rotated in a lefthand direction to make up the connections in a lefthand drilling string, or the like. It will be apparent that if this is desired a switch similar to the switch 87 may be arranged to be actuated by the web 71 when the motor 56 swings under a lefthand torque of a given intensity to effect the deenergization of the motor 56. In the case illustrated, however, a stop 90 is provided on the bracket 55 to limit or prevent swinging of the motor 56 when the outer part 13 is being driven in a lefthand direction. The parts may be related so that the spring 75 described above normally holds the motor 56 in a position where the cradle web 71 engages against the stop 90.

It is preferred to provide brake means to stop turning of the outer table part 13 to facilitate the positioning of the tong supporting unit carried by the outer table part. The brake means illustrated in the drawings includes a drum 91 connected with the motor shaft 57. The drum 91 may be connected with the coupling 58. A brake band 92 carrying a suitable friction material surrounds the drum 91 and is supported intermediate its ends by an adjustable anchor 93. The anchor 93 may be carried by a post 94 on the bracket 55. A lug 95 projects from an end of the brake band 92 and a spring 96 acts on the lug 95 to hold the brake band 92 in the released condition. A shaft 97 is turnably supported by the post 94 and a double-ended lever 98 is fixed to the shaft 97. A pivot 99 connects one end of the lever 98 with the other end of the brake band 92. A screw 100 is pivotally connected with the other arm of the lever 98 and extends through the spring 96 to the lug 95 of the brake band 92. A nut 101 on the screw 100 engages lug 95 to actuate the same upon turning of the lever 98.

A suitable brake operating linkage 102 is connected with a lever 103 fixed on the shaft 97. The linkage 102 extends to a point adjacent the post 86 carrying the manual switch 82 and is there provided with a pedal 103. The pedal 103 is conveniently operable by the operator controlling the switch 86. Upon depression of the pedal 103 the shaft 97 is turned to tighten the brake band 92 on the brake drum 91 and thus stop rotation of the outer table part 13. By appropriate operation of the switch 82 and the brake pedal 103, the outer table part 13 may be turned to any selected rotative position.

The tong supporting means 15 is provided to support a pair of tongs T for quick easy engagement with the string S above and below the joint or connection to be threaded or unthreaded. One unit of the tong supporting means 15 is fixed to the base 10 and the other unit of the means 15 is carried by the outer table part 13. The tong supporting unit of the means 15 on the base 10 includes a vertical post 104 removably secured to the base wall 19 and extending upwardly through an opening 105 in the ring 54. The post 104 may be secured to the wall 19 by any suitable quick connection means. For example, its lower end may be removably held in a socket 130 on the wall 19 by a screw 131. The unit of the tong supporting means 15 on the outer table part 13 includes a similar post 106 having a foot 107 bolted to the part 13. The post 106 is considerably taller than the post 104 but is otherwise of the same design. Stems 108 are shiftable and turnable in vertical openings 111 provided in the posts 104 and 106 and the stems are provided at their upper ends with heads 109. Springs 110 are arranged under compression between the lower ends of the stems 108 and the bottoms of the openings 111. The springs 110 counterbalance or partially counterbalance the stems 108 and the parts carried thereby. The stems 108 may be locked or secured in the adjusted positions by clamp screws 112. The heads 109 are provided with horizontal openings 113 to receive tong carrying levers or arms 114.

The arms 114 are shiftable and turnable in the openings 113 and project inwardly toward the string S when in the active positions. The tongs T are suitably secured to the inner ends of the arms 114. Slots 115 are provided in the heads 109 and the arms 114 have keys 116 adapted to engage in the slots 115 to hold the arms against turning. By shifting the arms 114 inwardly toward the center of the table their keys 116 may be disengaged from the slots 115 whereupon the arms may be reversed or turned 180° to invert the tongs T for right and lefthand operation. Stop heads 115a are provided on the arms 114 to limit this inward shifting of the arms and to prevent disengagement of the arms from the heads 109. Springs 116a may be arranged under compression between the heads 115a and shoulders 117 to urge the arms 114 outwardly so that their keys 116 remain in cooperation with the slots 115 during operation of the tongs T. The posts 104 and 106 are arranged to clear or pass one another during rotation of the table part 13. The head 109 and the arm 114 of the unit carried by the table part 13 pass freely over the head 109 and arm 114 of the tong supporting unit on the base 10. When the tongs T are not in use the heads 109 may be turned to positions where the arms 114 and the tongs T do not interfere with operations at the rotary table.

Means is provided for connecting the inner and outer table parts 11 and 13 for simultaneous rotation when it is desired to employ the torque controlled drive means 14 in the operation of well tools. The means for connecting the inner and outer table parts 11 and 13 may comprise bars 118 provided at their opposite ends with lugs 119. The lugs 119 are adapted to engage in suitable openings 120 and 121 in the tops of the table parts 11 and 13, respectively, whereby the bars 118 serve to connect the two table parts 11 and 13.

When the drilling string S is being rotated to

operate a drilling tool, or the like, the inner table part 11 is rotated by the drive means 14 in the usual manner and the outer table part 13 may remain stationary. At this time the heads 109 and the arms 114 may be in retracted positions where the tongs T are entirely clear of the inner table part 11 and the bushings carried thereby. When the drilling string S is being assembled or made up the slips 35 are employed as illustrated in Fig. 4 of the drawings to support the lower portion of the string S on the inner table part 11. The adjusting screw 132 may be set so that the mechanism will make up the connections under any selected torque. The heads 109 and the arms 114 are brought to positions such as illustrated in Figs. 1 and 4 of the drawings where the tongs T may engage about the upper and lower sections of the tool joint section or connection C being made up. The tongs T are supported in such a manner that they may be easily and quickly arranged in the operative positions about the parts of the coupling C. The tongs T are supported by the arms 114 and it is unnecessary to employ lines, cables, etc. to suspend and operate the tongs. When the tongs T have been properly engaged about the upper and lower sections of the connection C the forward button 83 of the manual switch 82 may be depressed to energize the motor 56. The motor 56 drives or rotates the outer table part 13 in a forward or righthand direction and the tong T carried by the outer table part is thus rotated relative to the lower tong T supported by the stationary base 10. Prior to the connection of the tongs T with the coupling C the threads of the coupling may have been manually started or mated. The rotation of the outer table part 13 and its tongs T by the drive 14 is continued until the threads of the connection or coupling C tighten. This tightening down of the threads of the coupling C of course increases the torque or load on the motor 56 and this increased load results in swinging of the motor 56.

When the threads of the coupling C have been tightened under a given rotational force the web 71 engages and operates the part 89 of the switch 87 to open the switch and thus cause de-energization of the motor 56. Thus the tightening of the coupling C ceases when the coupling has been tightened a suitable or selected amount. The tongs T are then disconnected from the string S and the string is lowered preparatory to connecting another stand of the pipe with the upper end of the string. The switch 82 and the brake pedal 103 may be manipulated to bring the tong supporting unit on the table part 13 to the correct position where its tong T may engage the upper section of the coupling C to be made up. The above operations may be repeated in making up the entire string S. The screw 132 may be adjusted so that the torque controlled drive means 14 assures the making up of the several connections C under a given rotational force. Accordingly, the string S may be made up in such a manner that its couplings are all secure but are not strained or galled.

When the string S is to be broken down the arms 114 are moved inwardly to disengage the keys 116 from the slots 115 and are turned 180° to invert the tongs T. The tongs T are engaged about the upper and lower sections of the tool joint or coupling C to be broken and the switch 82 is operated by depressing the button 85.

This energizes the motor 56 to turn the outer table part 13 in a counter-clockwise direction. The tongs T carried by the base 10 holds the lower part of the string S against rotation while the tongs T carried by the rotating table part 13 cause the upper stand or section of the string to rotate so that the threads of the coupling C are unthreaded. When the coupling C has been broken or unthreaded the tongs T are disengaged from the string S and the upper detached section or stand of pipe is removed and laid down or stacked in the derrick. The string S is raised to bring the next tool joint or coupling C above the rotary table and the above operations are repeated until the entire string is broken down.

In both making up and breaking down the joints of a well string, the stem 108 carried by the post 106 may be left free to shift vertically so that the tongs T engaging the upper stand or section of pipe may shift vertically while the threads are made up or unthreaded. In carrying out the above described operations a single operator observes the gauge 70 and may control the switch 82 and the brake 103 and two operators may manipulate the tongs T. The operations may be carried out rapidly with practically no danger to the workmen or equipment.

In the event that the main drive 12 for the inner table part 11 fails or is out of commission the inner and outer table parts 11 and 13 may be connected by means of the bars 118 so that the drive 14 may be utilized to operate the drilling tools. In this case the post 104 is detached from the base 10 and removed before the drive 14 is put into operation. In some cases it may be desired to employ the drive 14 to rotate the well string for special operations where a torque controlled drive is desired. The screw 132 may be adjusted so that the switch 87 operates to de-energize the motor 56 when any given or selected torque has built up in the drilling string.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A rotary table for well drilling comprising a rotatable inner table part, power means for rotating said inner part, a rotatable outer table part around said inner part, and a separate power means for rotating said outer table part.

2. A rotary table for well drilling comprising a base, an inner table part supported on the base for rotation, drive means for rotating the inner table part, an outer table part around the inner table part rotatably supported on the base independently of the inner table part, a separate drive for rotating said outer table part, and tong supporting means on the base and the outer table part.

3. A rotary table for well drilling comprising separately mounted rotatable inner and outer parts, drive means for rotating said inner part, separate drive means for rotating the outer part independently of the inner part, and a control for the last named drive means responsive to the resistance to rotation of the outer part.

4. A rotary table of the character described comprising a base, an inner part rotatably sup-

ported on the base, an outer part around the inner part rotatably supported on the base independently of the inner part, means on the base and outer part to support tongs for engaging a well string, power means for rotating the outer part relative to the inner part, and a control for de-energizing the power means responsive to the resistance to rotation of the outer part.

5. Apparatus for use with a rotary table having a drive comprising a rotatable part surrounding the table, an electric motor, a drive between the motor and the said part, a cradle supporting the motor to swing in response to resistance to rotation of said part, and a control responsive to swinging of the motor for de-energizing the motor when said resistance reaches a given value.

6. A rotary table of the character described comprising an inner part, a rotatable outer part around the inner part, means on the outer part to support tongs for engaging a well string, a motor, a drive between the motor and said outer part, means supporting the motor to move in response to resistance to rotation of the outer part, 25 a control circuit governing the motor, and means influencing said circuit to de-energize the motor when the motor moves a given distance.

7. A rotary table of the character described comprising an inner part, a rotatable outer part around the inner part, means on the outer part to support tongs for engaging a well string, a motor, a drive between the motor and said outer part, means supporting the motor to move in response to resistance to rotation of the outer part, 35 a control circuit governing the motor, manual switch means for said circuit operable to initiate and stop operation of the motor, and means influencing said circuit to de-energize the motor when the motor moves a given distance.

8. A rotary table of the character described comprising an inner part, a rotatable outer part around the inner part, means on the outer part to support tongs for engaging a well string, a reversible motor, a drive between the motor and said outer part whereby the motor rotates said outer part, means supporting the motor to move in response to resistance to rotation of the outer part in at least one direction, manual control means for initiating operation of the motor, and control means for stopping the motor in response to a given movement of the motor.

9. A rotary table of the character described comprising an inner part, a rotatable outer part around the inner part, means on the outer part to support tongs for engaging a well string, a reversible motor, a drive between the motor and said outer part whereby the motor rotates said outer part, means supporting the motor to move in response to resistance to rotation of the outer part in at least one direction, manual control means for initiating operation of the motor, control means for stopping the motor in response to a given movement of the motor, and means for adjusting the last named means to operate at a selected movement of the motor.

10. A rotary table of the character described comprising a base, an inner part rotatable on the base, an outer part around the inner part rotatably supported on the base independently of the inner part, means on the base and outer part to support tongs for engaging a well string, power means for rotating the outer part independently of the inner part, manual control means for starting and stopping the power means, and brake

means for stopping the said outer part in any selected position.

11. A rotary table of the character described comprising an inner part, a rotatable outer part around the inner part, power means for driving the inner part, power means for rotating the outer part independently of the inner part, a torque control for de-energizing the last named power means when there is a given resistance to rotation of the said outer part, and means for connecting the said inner part with said outer part to be driven by the said last named power means.

12. A rotary table of the character described comprising a base, a rotatable inner part on the base, an outer part around the inner part rotatably supported on the base independently of the inner part, releasable means for connecting the said parts to rotate together, a power means, a drive between the power means and the said outer part, a second power means, and a drive between 20 said second power means and said inner part.

13. A rotary table comprising a base, an inner table part supported on the base for rotation, drive means for rotating the inner table part, an outer table part around the inner table part rotatably supported on the base independently of the inner table part, and a separate drive for rotating said outer table part.

14. In a rotary table, the combination of a base, an inner table part rotatably supported on the base, an outer table part around the inner table part rotatably supported on the base independently of the inner part, and anti-friction hold-down means on the base holding the outer part against upward displacement.

15. In a rotary table, the combination of a base,

5 an inner table part rotatably supported on the base, an outer table part around the inner table part, a trough flange on the base, and anti-friction bearing means in the flange supporting the outer part on the base for independent rotation, the flange being adapted to contain lubricant.

16. In a power driven rotary table, the combination of a base, an inner table part supported on the base for rotation, and an outer table part around the inner table part rotatably supported on the base independently of the inner table part.

17. In a rotary table for handling a well string having threaded couplings, a stationary base, inner and outer table parts separately mounted 15 on the base for independent rotation, a tong supporting unit on the outer part rotatable therewith to support tongs where they may grip the upper part of a well string coupling above said table parts, and a tong supporting unit fixed to the stationary base inside of the outer part and projecting upwardly therefrom to support tongs where they may grip the lower part of the well string coupling above said table parts.

18. In a rotary table, a stationary base, inner and outer table parts separately mounted on the base for independent rotation, means on the inner part for supporting a well string, a unit on the outer table part for supporting upper string-engaging tongs, there being a space between the periphery of the inner table part and the outer table part, a second unit for supporting lower string-engaging tongs, and means extending through said space for securing said second unit to the stationary base.

GUY K. CLAIRE.
